George B. Pickop,
by *Alfred J. Pickop*,
his attorney.

UNITED STATES PATENT OFFICE.

GEORGE B. PICKOP, OF NEW HAVEN, CONNECTICUT, ASSIGNOR TO THE MALLEABLE IRON FITTINGS COMPANY, OF BRANFORD, CONNECTICUT, A CORPORATION OF CONNECTICUT.

METHOD OF MAKING VIBRATOR-BODIES.

1,268,487.

Specification of Letters Patent.

Patented June 4, 1918.

Original application filed August 21, 1915, Serial No. 46,711. Divided and this application filed December 21, 1916. Serial No. 138,210.

To all whom it may concern:

Be it known that I, GEORGE B. PICKOP, a citizen of the United States, residing in the city and county of New Haven, State of Connecticut, have invented certain new and useful Improvements in Methods of Making Vibrator-Bodies, of which the following is a full, clear, and exact description.

My invention relates to percussive tools and more particularly to vibrators of the reciprocating piston type used in the molding art for facilitating the removal of the pattern. These vibrators are usually actuated by compressed air and their construction is such that the piston is rapidly reciprocated when and so long as the vibrator is placed in free communication with the source of air, thereby imparting to the pattern board, to which the vibrator is attached, the vibration necessary to free the pattern properly from the mold.

One of the objects of the present invention is to provide a very efficient vibratory device which can be readily and inexpensively manufactured. More particularly my object is to provide a vibrator of which the body portion is cut from a commercial rolled bar or rod, for example, a hexagonal steel bar, and wherein most of the operations incident to the manufacture of the vibrator body from such rod or bar can be carried out by automatic machinery. Thus a large number of my improved vibrators may be produced in a relatively short time at a very low cost.

I also aim to improve the general construction and operation of devices of the class to which the invention relates.

With these and other objects in view the invention consists in the novel features, steps and combinations of parts to be hereinafter described and claimed.

In the accompanying drawing,

Figure 1 is a side elevation of a vibrator embodying my invention showing the means for attaching the same to the pattern board;

Fig. 2 is a top plan view of the parts shown in Fig. 1;

Fig. 3 is a section on line 3-3, Fig. 1; and Figs. 4, 5, 6 and 7 are sections on lines 4-4, 5-5, 6-6, and 7-7 of Fig. 1.

In the form shown the vibrator has a

body 10, constructed from a length of hexagonal bar, preferably of steel. This body 10 is provided with a cylindrical bore 11, 55 which is closed at the ends by plugs or caps 12, 13 respectively, and forms a cylinder in which an elongated piston or plunger 14 is adapted to reciprocate. It will be observed that in the form illustrated the cylinder 11 60 is eccentrically located with respect to the hexagonal body 10, so that the wall 10^a at one side of the cylinder is considerably thinner than the wall 10^b at the opposite side; and the thicker cylinder wall 10^b is 65 used as a sort of air chest in which the air passages for connecting the cylinder with the source of compressed air are formed. The air chest 10^b is of less length than the vibrator body 10 owing to the fact that the 70 ends of the latter are reduced and formed as cylindrical extensions 15 in line with the cylinder 11. The cap 12 is screwed into a threaded socket in one of the extensions 15 and the cap 13 is screwed into a threaded 75 socket in the other cylinder extension, the caps being preferably interchangeable. Preferably the caps 12, 13 are cut from bar stock (in the case illustrated a hexagonal bar of somewhat less diameter than the body 80 10), and the cap or plug 13 has its head cut away at one side to form a notch 16, adapted to seat on the edge of the pattern board 17, in the manner shown. At the opposite side of the head of the plug 13 a 85 smaller notch 18, is formed which serves as a seat for a nut 19. A bolt 20, having a screw head 21, is passed through a hole 22, cut in the pattern board, and an alined hole 23, passing transversely through the head 90 of the plug 13 and communicating with the respective notches 16, 18. This bolt 22, engages the nut 19, and as the latter is prevented from turning by engaging the side wall of the notch 18, the turning of the bolt 95 will tightly clamp the cap 13, and the vibrator as a whole to the pattern board. By this construction the vibrator can be very conveniently applied to the pattern board by the use of a minimum number of 100 parts.

The portion 10^b of the vibrator body is provided with a central screw threaded inlet 24, to receive the threaded end of a pipe

or fitting in communication with the pressure source (not shown). Passages 25, 26 lead from the port 24, (at points adjacent the bottom of said port or pocket) to ports 27, 28, in the cylinder wall, and these latter ports are adapted to communicate by means of annular grooves, 29, 39 on the piston 14, with ports 31, 32. The ports 31, 32 enable air to pass out of the cylinder ducts or passages 33, 34 respectively which communicate with ports 35, 36 at the respective ends of the cylinder 11. The piston 14 is provided with end stops 14^a, 14^b which are so formed as to prevent the ends of the cylinder from being closed off, and a spring 14^c acts on the piston in such a manner as to normally hold the latter against one end of the cylinder. Near the respective ends of the cylinder a plurality of exhaust ports 37, 38 are cut in the thin wall 10^a.

The normal position of the piston is shown by dotted lines in Fig. 1. Supposing now that the air is admitted to the port or inlet socket 24, it will pass through duct 26, port 28, groove 30, port 32, duct 34 and port 36 to the right-hand end of the cylinder so as to act on the right-hand head of the piston and throw the latter to the left in opposition to the spring 14^c. When this operation takes place the duct 25, is cut off because a solid portion of the piston is located over the port 27. However, when the piston moves to the left the port 27, is opened as soon as the groove 29, comes into line with it and communication is then established through port 31, duct 33 and port 35 with the left-hand end of the cylinder so that the piston is thrust to the right. The exhaust takes place through the ports 37, 38 in the usual manner, and a rapid vibration is kept up until the air supply is cut off. The spring 14^c normally holds the piston in such a position that it will begin to vibrate at once. The piston is reversible and the spring 14^c may be used at either end of the cylinder.

In manufacturing an improved vibrator of the type shown, I take a hexagonal bar preferably of steel and at suitable points cut it down to form the reduced cylindrical extensions or portions 15. Preferably a number of the vibrators will be made at once and the eccentric portions formed by turning will be twice the width of the portion 15, so that by cutting off the bar at the centers of the several cylindrical portions a plurality of vibrator bodies 10 with rounded end extensions 15, will be formed. Each vibrator body is then bored out to form the cylinder 11, and the ends of the cylinder are tapped for the reception of the caps or plugs 12, 13. The socket 24, is drilled in the portion 10^b of the body and the ducts 25, 26, 33, 34 are formed by drilling the part 10^b from the respective ends. The drill holes are on a slant so that while the drill may be set

against the narrow end face of the part 10^b it will reach the bottom of the socket 24, whereby the passages 25, 26 will not be cut off by the connecting pipe or its equivalent when the same is screwed into the socket to a sufficient extent to secure it firmly in place. The several ports in the cylinder wall are formed by drilling the walls 10^a, 10^b transversely, and in the part 10 the drilled holes for both ports and ducts are partially plugged up in such a manner as to provide the described passages or communications, as indicated by the dotted lines in Fig. 3.

The vibrator body is of such form that it can be evenly tempered without difficulty, and I prefer to harden the vibrator in this manner. The device can be very accurately constructed so as to be economical in consumption of air and powerful in action. Furthermore my improved vibrator while very serviceable and durable, can be produced at very low cost by the use of commercial bar stock and of the automatic machinery to which such stock is well adapted.

I do not claim herein the improved vibrator as an article of manufacture as claimed in my application, Serial No. 46,711, filed August 21, 1915, of which the present application is a division.

What I claim is:

1. The method of making a vibrator body from commercial bar stock, which comprises drilling a longitudinal bore eccentrically through a commercial bar to produce opposite walls of unequal thickness, drilling intake passages in the thicker wall of the bore, and drilling exhaust ports in the thinner wall of the bore; substantially as described.

2. The method of making a vibrator body which comprises drilling a longitudinal bore eccentrically through a polygonal bar, cutting away a portion of the ends of the bar to produce shoulders, drilling intake ports in the thicker wall of the bore through said shoulders, and forming exhaust ports in the thinner wall of the bore; substantially as described.

3. The method of making a vibrator body which comprises drilling a lengthwise bore eccentrically through a polygonal bar, rounding off the ends of the bar to form reduced extensions, and drilling intake passages in the thicker wall of the bore from the extremities of the polygonal body portion which are adjacent the rounded off ends.

4. The method of making a vibrator body which comprises cutting a length of metal from a commercial bar, drilling a longitudinal bore eccentrically through said length of metal so that the resulting body is thicker at one side than at the other, drilling intake passages in the thicker wall of the body, and drilling exhaust passages in the thinner wall of the body; substantially as described.

5. The method of making a vibrator body,

which comprises cutting a length of metal from a commercial bar of uniform cross-section, reducing the diameter of the end portions of such length of metal so as to 5 form shoulders, drilling a longitudinal bore through such length of metal from end to end, drilling inlet passages in the wall of the body at one side, from the aforesaid shoulders, and drilling an intermediate inlet 10 socket with which said passages communicate; substantially as described.

6. The method of making vibrator bodies, which comprises turning down a commercial bar at different points in the length thereof 15 to create reduced rounded portions at different points, dividing the bar into a plurality of lengths by cutting through each of the reduced rounded portions so that a plurality of bodies are formed having reduced rounded ends and adjacent shoulders, drilling a longitudinal bore through each body, and drilling passages in the wall of the body from the shoulders adjacent the reduced end portions; substantially as de- 20 scribed.

7. The method of making vibrator bodies, which comprises reducing a polygonal bar 25

at different points in its length to create eccentric rounded portions therein, dividing the bar into a plurality of lengths by cutting through each of said eccentric rounded portions so that a plurality of polygonal bodies are formed having reduced rounded ends, drilling a longitudinal bore through each body concentrically with the eccentric rounded ends, drilling inlet passages in the thicker wall of the bore, and drilling exhaust 30 35 passages in the thinner wall of the bore; substantially as described.

8. The method of making a vibrator body 40 from commercial bar stock, which comprises cutting a length of metal from a commercial bar of uniform cross section, cutting away a portion of the ends of the bar to form shoulders, drilling a longitudinal bore eccentrically through such length of metal to produce opposite walls of unequal thickness, drilling inlet passages in the thicker wall of the body from the aforesaid shoulders, and drilling exhaust ports in the thinner wall 45 50 55 of the bore; substantially as described.

In witness whereof, I have hereunto set my hand on the 15th day of December, 1916.

GEORGE B. PICKOP.
